UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

LOOPER-THREAD-CONTROLLING MECHANISM FOR SEWING MACHINES.

Application filed August 7, 1923. Serial No. 656,268.

The invention relates to new and useful improvements in looper thread controlling mechanisms for sewing machines, and more particularly to a looper thread controlling mechanism for a sewing machine having a cylindrical work supporting arm within which the looper operating mechanism is disposed.

An object of the invention is to provide a looper thread controller for a machine of the above type which includes means for pulling thread from the supply for the looper, which thread pulling means is so constructed as to pull off varying amounts of thread according to the length of the feed.

A further object of the invention is to provide a mechanism of the above type wherein when the feed is adjusted for varying the length of the feed stroke, the amount of thread pulled off is automatically varied in proportion to the variations in the feed.

A further object of the invention is to provide a thread controlling mechanism of the above type which also includes means for taking care of the slack during the operations of the looper.

A still further object of the invention is to provide a mechanism of the above type wherein the pull off means and the thread controlling means are both operated from the looper supporting shaft.

A still further object of the invention is to provide a thread controlling mechanism of the above type wherein the cooperating elements of the pull off in addition to their movements relative to each other for pulling off thread are moved back and forth by the feeding mechanism in a direction substantially at right angles to the thread pulling movements thereof, and wherein the cooperating thread pulling elements derive their movements from different parts of the feeding mechanism so that the variation in the length of the feed will vary the amount of thread pulled off.

A still further object of the invention is to provide a slack thread controller for the looper mechanism having an oscillating shaft moved endwise for giving a lateral movement to the looper, wherein said slack thread controlling mechanism is operated by said looper shaft and moves bodily therewith during its endwise movements.

These and other objects will in part be obvious and will in part be hereinafter more fully disclosed.

In the drawings which show by way of illustration one embodiment of the invention—

Fig. 1 is a top plan view of the cylindrical work support with the cover plate and end cap removed;

Fig. 2 is a longitudinal vertical section through the cylindrical work supporting arm and showing the feeding mechanism and thread controlling devices in side elevation;

Fig. 3 is a transverse sectional view on the line 4—4 of Fig. 2;

Fig. 4 is a longitudinal sectional view through the extreme rear end of the feed bar, and the parts of the machine adjacent thereto;

Fig. 5 is a perspective view of the bracket for shifting the thread guides with which the pull off cam cooperates;

Fig. 6 is a perspective view of the link for moving the feed bar endwise and showing the projecting arm which shifts the bracket carrying the thread guides cooperating with the pull off cam;

Fig. 7 is a perspective view of one member of the thread clamp;

Fig. 8 is a perspective view of the sleeve which carries the thread guides cooperating with the take up cam;

Fig. 9 is a side view of the thread guides cooperating with the pull off cam;

Fig. 10 is an end view of the same;

Fig. 11 is a side view of said thread guides as viewed from the otherside thereof;

Fig. 14 is a plan view of the same thread guides;

Fig. 15 is a detail in section showing the means for preventing the sleeve carrying the guides with which the pull off cam cooperates from oscillating with the looper shaft,

Fig. 16 is a detail in section showing the means for preventing the guides cooperating with the slack thread control cam from oscillating with the looper shaft, and

Fig. 17 is a detail showing the take-up cam and looper thread operated upon thereby.

The invention is directed broadly to a looper thread controlling mechanism and more particularly to a looper thread controlling mechanism for a cylindrical work supporting arm within which the looper mechanism is packed. Said looper mechanism includes a shaft running lengthwise of the arm on which the looper or loopers, if more than one looper is used, are rigidly mounted. This shaft is oscillated and moved endwise so as to oscillate the loopers and give thereto a lateral movement.

The material is fed on to the arm during sewing by a feed dog carried by a feed bar which extends lengthwise of the arm. Said feed bar is raised and lowered by means of an eccentric on the looper supporting shaft and it is moved endwise for the purpose of feeding the material by a rock frame operated from the cross shaft in the standard of the machine. This rock frame has a slotted extension to which the link is adjustably connected. This link in turn is connected to the feed bar and moves it endwise. Mounted on the looper supporting shaft is a bracket carrying a pull off cam which oscillates with the looper shaft and which moves back and forth with the feed bar. Cooperating with said pull off are thread guides through which the thread passes, and these thread guides lay the thread in the path of the pull off cam. These thread guides are carried by a bracket which is mounted on the looper supporting shaft so as to slide freely thereon. The link which moves the feed bar back and forth has a depending arm carrying the pivoted block which rides in a groove or recess in the bracket carrying the thread guides. This depending arm is oscillated to a certain extent by the means which moves the feed bar back and forth and the extent of its oscillation is determined by the length of the stroke of the feed bar, and varies according to the length of the reciprocations in the stroke of the feed.

The pull off cam also moves back and forth with the feed bar, but always has the same relative movement imparted thereto as is given to the feed bar. The thread guides, however, have a varying movement imparted thereto, depending upon the length of stroke of the feed bar. When the length of the feed stroke is increased, then said thread guides are moved to a greater extent. Thus it is that the amount of thread pulled off is determined by the length of feed. There is a thread clamp between the pull off and the loopers which clamps the thread while the same is being pulled from the supply. There is also a take up cam operating upon the looper thread between the thread clamp and the loopers.

The invention will possibly be better understood by a detail reference to the draw-

ings. The type of machine in which the invention is embodied is the same as that shown and described in detail in the patent granted to N. D. Clark, December 31, 1918, No. 1,289,663. It will not be necessary to go into any great length of description of the general parts of the machine. It is thought sufficient to point out that the machine contains two needles 1, 1, carried by a needle bar 2' which is vibrated by the usual needle lever. Cooperating with the needles beneath the work support are loopers 2, 2 which are mounted on a looper supporting shaft 3, which shaft is oscillated by suitable mechanism located in the standard 4 of the machine. The mechanism within said standard is similar to that shown in Patent No. 583,414, granted Muther et al., dated May 25, 1897, and has not been shown nor described in this application. The material is fed up the work support as it is stitched by means of a feed dog 5 which cooperates with a pressure foot of the usual construction. The feed dog 5 is carried by a feed bar 7. This feed bar extends lengthwise of the machine, and at its rear end is forked as at 8 so as to engage a slabbed pin 9 carried by a rock frame 10. Said rock frame 10 is provided with a slotted bracket 11. A link 12 is pivoted to a bolt 13 adjustable in said slotted bracket. Said link at its other end is pivoted at 14 to the feed bar. When the rock frame 10 is oscillated, it will impart endwise movement to the link 12, and this in turn will move the feed bar back and forth, the forked end sliding on the slabbed pin. In order to adjust the length of the stroke of the feed, the link 12 is adjusted toward or away from the center of the rock frame 10. This is accomplished by loosening the bolt 13 in the slot of the rock frame and shifting the end of the link. When the link is moved toward the pivot 42 of the rock frame, the stroke of the feed bar is shortened, and when it is moved outwardly away from the pivot 42, then the stroke of the feed bar is increased. The feed bar is raised and lowered by means of a collar 15 which cooperates with an eccentric 16 on the looper supporting shaft.

The looper threads *t* are led through suitable tensions and thence through a tube 18 which carries the threads down into a work supporting arm. Said threads after they leave the tube 18 pass to the thread guide 19 and thence to the thread guide 20. These thread guides 19 and 20 are formed in a bracket 21. Said bracket 21 has a supporting shank 22 on which is mounted an upwardly projecting U-shaped part in which the thread guides 19 and 20 are formed. This U-shaped part is formed with an inclined thread slot 23 which extends to the thread guides 19 and 20. The thread guides 19 and 20 are closed eyes except for the

slot 23 leading thereinto. There is a projecting member 24 carried by the U-shaped part in which the thread guides are formed which is adapted to receive the thread and direct it into the slot 23. There is a projecting member 25 which is spaced slightly from the wall of the part having the thread guide 20 formed therein, and which is bent so as to slightly overhang said wall, which 5 operates to prevent the thread from drawing back up into the slot 23 when the thread passes from the thread guide 20 toward the forward end of the machine. This provides a pair of spaced thread guides which may 10 be readily threaded. Cooperating with said thread guides is a pull off cam 26. Said pull off cam 26 is rigidly secured to an outwardly projecting arm 27 carried by a sleeve 28 (see Fig. 3). This sleeve 28 is mounted 15 freely on the looper supporting shaft. Said sleeve, however, is held from rotation on said shaft by means of a forked bracket 29 carried by a collar 30 secured to the looper supporting shaft by a set screw 31. The 20 sleeve 28 has a depending lug 32 which extends between the forked arms 29 as clearly shown in Figures 4 and 5. These forked arms do not prevent the sleeve from moving endwise on the looper supporting shaft. Said sleeve 28 is located between the connected collars 33 and 34 which are likewise 25 freely mounted on the looper supporting shaft 3. The collar 33 has a recess 35 formed therein and a screw pin 36 carried 30 by the feed bar, passes down into said recess 35. The result is that the connected collars 33 and 34 will be moved back and forth with the feed bar and these collars will cause the sleeve 28 and the pull off cam 35 carried thereby to move back and forth on the looper supporting shaft in unison with the feed bar. This pull off cam 26 oscillates 40 between the thread guides 19 and 20 and will engage the looper threads running from one guide to the other.

The supporting shank 22 on which the thread guides 19 and 20 are mounted, is in turn mounted in an arm 37 carried by a sleeve 38 mounted to slide freely on the looper supporting shaft. The link 12 which moves the feed bar back and forth has a depending arm 39 on which is pivoted a block 40. The sleeve 38 is provided with a recess 41 in which the block 40 engages. It will readily be seen that when the link 12 is shifted for varying the stroke of the feed bar, the arm 39 will be shifted, and this in turn will shift the block 40 and move the sleeve 38 to an extent depending upon the extent to which the link is shifted.

During the operation of the machine, the oscillations of the looper shaft impart an oscillation to the thread cam 26. This is brought about by reason of the fact that while the sleeve 28 carrying the cam 26 is

freely mounted on the looper shaft, said sleeve has a lug 32 extending between the forked arm 29 carried by the collar 30 which in turn is secured to the looper shaft (see Fig. 4). While this cam 26 is oscillated with the looper shaft, it is free to move endwise on the looper shaft for reasons which will be stated later. The member 22 carrying the thread eyes 19 and 20 is mounted on the arm 37 formed as a part of the sleeve 38. This sleeve 38 is freely mounted on the looper shaft so that it may be moved endwise thereof, but it is held from oscillation with the looper shaft by its sliding connection with the guide 69. From the above it will be noted that the thread eyes are stationary and the thread cam oscillates back and forth between the thread eyes, and thus it is that the cam comes in contact with the looper thread passing through the thread eyes, and pulls thread from the supply at the proper time. The amount of thread pulled off is determined by the shaping of the cam and the position of oscillation of the cam relative to the thread eyes. The thread eyes and the cam move back and forth with the feed bar, but this movement imparted to these members of the pull off mechanism, does not operate in any way to pull thread; their relation to each other in their lateral movement is maintained always the same. Nevertheless, when the stroke of the feed bar is adjusted, then the relative oscillating positions of these parts is changed. The thread eyes are connected as above noted to an arm which is formed as a part of the link which is shifted for varying the stroke of the feed, and therefore, when this link is shifted, it will shift the position of the thread eyes. When you shift the link to lengthen the feed, then the thread eyes are moved closer to the path of oscillation of the pull off cam, and more thread is pulled off, and when the link is shifted to shorten the feed, then the thread eyes are moved away from the path of oscillation of the pull off cam, and less thread is pulled off.

The looper threads after leaving the thread guide 20, pass to the thread clamp which consists of a stationary member 43 mounted on the work supporting arm by means of a shank 44 and the clamp screw 45 which passes through an opening in said shank and threads into the work supporting arm. Said stationary thread clamp 43 is bent so as to form a yielding member 46 which is slotted at 47 so that the thread running alongside of the stationary thread clamp 43 and into the slot 47, will pass in rear of the yielding member 46. Mounted on the looper supporting shaft is a sleeve 48. Said sleeve is secured to the shaft so as to move endwise with the shaft, but the sleeve does not oscillate with the shaft. There is a collar 49 rigidly secured to the looper shaft at one

end of the sleeve 48 and another collar 50 rigidly secured to the shaft at the other end of said sleeve. Formed on this sleeve 48 is a plate 51 which is adapted to cooperate 5 with a yielding member 46 so as to clamp the thread against said yielding member. The plate 51 is formed integrally with sleeve 48. The thread after it leaves the thread clamp, passes through a thread guide 52 10 formed in a bracket 53. Said bracket 53 is provided with a shank 54, which extends into a slot 55 in the sleeve 48, and an overlying plate 56 secured to said sleeve by a screw 57 rigidly secures the shank to the 15 sleeve. Said bracket 53 is provided with an inclined thread slot 58. The bracket is bent into a U-shaped member, and has the thread guide 59 directly opposed to the guide 52. The slot 58 leads to both guides 52 and 20 59. The bracket 53 has a forwardly projecting finger 60 which directs the thread down into the slot 58. It also has a member 61 which is provided with a projecting end 62 which retains the thread in the thread guide 25 59. The thread after leaving the guide 59 passes around the end 62 and in rear of the finger 63 carried by the bracket 53. These fingers aid in the properly directing of the thread during the threading up of the machine. The thread then passes in rear of 30 the thread guiding hook 64 and through an opening 65 in the bearing 66 for the looper shaft to the eyes of the thread carrying loopers. The bracket 53 moves back and 35 forth with the thread carrying looper. Cooperating with these thread guides 52 and 59 is a take-up cam 67, which take-up cam is carried by the sleeve 49. The take-up cam therefore, not only oscillates with the 40 looper supporting shaft but moves endwise therewith, so that the slack thread controlling mechanism moves endwise with the looper supporting shaft, and therefore, said thread take-up members will have no effect 45 upon the thread passing to the loopers, except the action of the take-up cam on the thread as it vibrates back and forth and comes into engagement with the thread passing between the thread guides.

50 The sleeve 38 which supports the guides cooperating with the pull off cam is held from oscillating with the looper shaft by means of a projecting lug 68 on said sleeve, extending between guides 69 fixed to the 55 work supporting arm. The sleeve 48 is likewise held from oscillating by means of a lug 70 projecting therefrom and cooperating with guides 69 carried by the work supporting arm.

Operation.

It is thought that the operation of my improved looper thread controlling mechanism will be obvious from the detailed description

which has been given above. As the loopers move forward to enter the needle thread loops, the slack thread controlling cams engage the looper thread and take up the slack so as to prevent the thread from buckling in front of the looper. When the looper starts on this retracting movement, the slack thread controlling cam will again take up the slack thread so as to insure that the thread running from the eye of the looper to the previous stitch will be substantially taut at the time when the point of the needle passes between said looper thread and the body of the looper which insures that the thread triangle shall be spread and held so that the needle will surely enter the same. When the loopers are being retracted, the thread clamp clamps the thread and the pull off operates to pull off thread for the next stitch. The pull off cam is oscillated by the looper shaft and the amount of thread pulled off is determined by the position of the thread eyes and the pull off cam, which are in turn determined by the movements of the feed bar on the one hand, and the position of the link which operates the feed bar on the other hand. Thus it is that the amount of thread pulled off varies according to the length of the stitch.

In Fig. 17 of the drawings, I have shown in detail the take-up cam for the looper thread which is engaged thereby. As the take-up cam moves downwardly, the thread between the eyes of the thread guide 52 takes the position as shown in the dotted lines at *a*. As soon as the needles are completely through the triangle, the high point of the cam 67^a passes the looper thread and the thread slips up along the portion 67^a into the cut-away portion of the cam at the upper portion thereof, and therefore, the thread becomes slack. This slack position of the thread is indicated at *b*. The cam is cut away so as to produce a comparatively loose looper thread at all times except when the needles are entering the looper thread triangle, and this results in a more elastic stitch.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. The combination with a feeding mechanism including a feed dog and means for varying the stroke of the feed dog; of a pull-off mechanism including thread guides, a pull-off member and means for giving said thread guides and pull-off member a relative movement of a fixed extent for pulling thread from the supply, and means for auto-

matically shifting the relative path of movement of the guides and the pull-off member upon the varying of the length of the feed.

2. The combination with a feeding mecha-

5 nism including a feed dog and means for varying the stroke of the feed dog; of a pull-off mechanism including thread guides, a pull-off member and means for giving said thread guides and pull-off member a relative 10 movement of a fixed extent for pulling thread from the supply, means for moving said thread guides and pull-off member back and forth with the feed dog, said means including devices for automatically shifting 15 the relative path of movement of the guides and pull-off member when the length of feed is varied.

3. The combination with a feeding mecha- 20 nism including a feed bar, a feed dog carried thereby, means for reciprocating the feed bar including devices whereby the stroke of the feed dog may be varied; of a pull-off mechanism including a movable pull-off cam member, thread guides co- 25 operating with said thread cam member, means for imparting a relative oscillating movement to said cam member, and guides of a fixed extent for pulling thread from the supply, and means for automatically shifting 30 the relative path of movement of the guides and cam member upon the varying of the length of the feed whereby the amount of thread pulled off automatically varies to accord with the length of stitch.

35 4. The combination with a feeding mecha- nism including a feed bar, a feed dog carried thereby, means for reciprocating the feed bar including devices whereby the stroke of the feed dog may be varied; of a pull-off 40 mechanism including a movable pull off cam member movable back and forth in unison with the feed bar, thread guides cooperating with said pull off member and movable back and forth with the feed bar, means for moving 45 said cam member relative to said guides for pulling thread from the supply, said thread guides being connected to the devices which vary the stroke of the feed dog so that the amount of thread pulled off is de- 50 termined by the length of the feed.

55 5. The combination with a feeding mecha- nism including a feed bar, a feed dog carried thereby, means for varying the stroke of the feed dog, a looper mechanism including a looper shaft, loopers rigidly carried by said shaft, said looper shaft having an endwise and an oscillating movement; of a pull off 60 mechanism including thread guides freely supported by said looper shaft, a pull off cam freely supported by said looper shaft, means for causing said pull off cam to oscillate with the looper shaft, means for moving said oscillating cam back and forth with the feed bar, and means for moving said thread guides back and forth with the feed bar and

shifting the position of the thread guides when the length of the feed stroke is varied so that the amount of thread pulled off is varied with the length of the feed stroke.

6. A sewing machine including a cylindrical work supporting arm, a looper shaft extending endwise thereof and carrying loopers, said shaft being adapted to oscillate and move endwise, a feed bar extending lengthwise of said arm and carrying a feed dog, means for moving said feed bar back and forth including devices whereby the stroke of the feed bar may be varied, a pull off mechanism including a pull off cam oscillating with the looper shaft, means for supporting said pull off cam on the looper shaft whereby the same can move endwise on the shaft, means connected with the feed bar for moving said pull off cam in unison with the feed bar, thread guides with which said pull off cam cooperates, and means for moving said thread guides with the pull off cam and for varying the position of the thread guides according to the length of feed.

7. A sewing machine including a cylindrical work supporting arm, a looper shaft extending endwise thereof and carrying loopers, said shaft being adapted to oscillate and move endwise, a feed bar extending lengthwise of said arm and carrying a feed dog, means for moving said feed bar back and forth including devices whereby the stroke of the feed bar may be varied, a pull off mechanism including a pull off cam oscillating with the looper shaft, means for supporting said pull off cam on the looper shaft whereby the same can move endwise on the shaft, means connected with the feed bar for moving said pull off cam in unison with the feed bar, a sleeve freely mounted on said looper shaft, thread guides carried by said sleeve with which said pull off cam cooperates, and means for connecting said sleeve with the devices for operating the feed whereby said thread guides are moved back and forth with the pull off cam and the position thereof varied when the length of feed is varied so that the amount of thread pulled off varies with the length of feed.

8. A sewing machine including a cylindrical work supporting arm, a looper shaft extending endwise thereof and carrying loopers, said shaft being adapted to oscillate and move endwise, a feed bar extending lengthwise of said arm and carrying a feed dog, a rock frame, a link having adjustable connection with the rock frame and pivoted to the feed bar for moving said feed bar back and forth, the adjustments of said link varying the stroke of the feed bar, a pull off mechanism including thread guides, a sleeve carrying said thread guides, said link having a rigid projecting arm connected to said sleeve whereby said sleeve is moved back and forth with the feed bar and is shifted

when the stroke of the feed bar is varied, and a pull off cam moving back and forth through the feed bar and moving between said thread guides for pulling off thread 5 from the supply.

9. A sewing machine including a cylindrical work supporting arm, a looper shaft extending lengthwise thereof and carrying loopers, said shaft being adapted to oscillate 10 and move endwise, a feed bar extending lengthwise of said arm and carrying a feed dog, a rock frame having a slotted bracket, a link having a shiftable connection with said slotted bracket at one end thereof and 15 pivoted to the feed bar at the other end thereof, said link having a rigid arm projecting therefrom at an angle to the longitudinal axis of the link, thread guides, a sleeve carrying said thread guides, said 20 sleeve having a connection with said arm whereby said sleeve moves back and forth with the feed bar and is shifted when the stroke of the feed bar is varied, and a pull off cam moving back and forth with the 25 feed bar and moving between said thread guides for pulling thread from the supply.

10. A sewing machine including a cylindrical work supporting arm, a looper shaft extending lengthwise thereof and carrying loopers, said shaft being adapted to oscillate 30 and move endwise, a feed bar extending lengthwise of said arm and carrying a feed dog, a rock frame having a slotted bracket, a link having a shiftable connection with 35 said slotted bracket at one end thereof and pivoted to the feed bar at the other end thereof, said link having a rigid arm projecting therefrom at an angle to the longitudinal axis of the link, thread guides, a 40 sleeve carrying said thread guides, said sleeve having a connection with said arm whereby said sleeve moves back and forth with the feed bar and is shifted when the stroke of the feed bar is varied, a pull off cam moving back and forth with the feed 45 bar and moving between said thread guides for pulling thread from the supply, said sleeve carrying the thread guides being freely mounted on said looper supporting 50 shaft, and means for preventing said sleeve from oscillating with the shaft.

11. A sewing machine including a cylindrical work supporting arm, a looper shaft extending lengthwise thereof and carrying 55 loopers, said shaft being adapted to oscillate and move endwise, a feed bar extending lengthwise of said arm and carrying a feed dog, a rock frame having a slotted bracket, a link having a shiftable connection with 60 said slotted bracket at one end thereof and pivoted to the feed bar at the other end thereof, said link having a rigid arm projecting therefrom at an angle to the longitudinal axis of the link, thread guides, a 65 sleeve carrying said thread guides, said

sleeve having a connection with said arm whereby said sleeve moves back and forth with the feed bar and is shifted when the stroke of the feed bar is varied, a pull off cam moving back and forth with the feed 70 bar and moving between said thread guides for pulling thread from the supply, a sleeve freely mounted on said looper supporting shaft and carrying said pull-off cam, and means whereby said sleeve is held from rotating on said looper supporting shaft. 75

12. A sewing machine including a cylindrical work supporting arm, a looper shaft extending lengthwise thereof and carrying loopers, said shaft being adapted to oscillate 80 and move endwise, a feed bar extending lengthwise of said arm and carrying a feed dog, a rock frame having a slotted bracket, a link having a shiftable connection with said slotted bracket at one end thereof and pivoted to the feed bar at the other end thereof, said link having a rigid arm projecting therefrom, at an angle to the longitudinal axis of the link, thread guides, a 85 sleeve carrying said thread guides, said sleeve having a connection with said arm whereby said sleeve moves back and forth with the feed bar and is shifted when the stroke of the feed bar is varied, a pull off cam moving back and forth with the feed 90 bar and moving between said thread guides for pulling thread from the supply, a sleeve freely mounted on said looper supporting shaft and carrying said pull off cam, means whereby said sleeve is held from rotating on said looper supporting shaft, and means connected to the feed bar for moving the 95 sleeve endwise of the looper supporting shaft. 100

13. A sewing machine including in combination a cylindrical work supporting arm, a looper shaft extending longitudinally thereof, loopers carried thereby, said shaft being adapted to oscillate and move endwise, a slack thread controlling mechanism including an oscillating cam fixed to the looper supporting shaft, thread guides mounted on the looper supporting shaft and movable endwise therewith, and means for preventing 105 said thread guides from oscillating with the looper supporting shaft. 110

14. A sewing machine including in combination a cylindrical work supporting arm, a looper shaft extending endwise thereof, loopers mounted on said shaft, said looper shaft being oscillated to move the loopers into and out of their needle thread loops and being moved endwise to give said loopers a needle avoiding movement, a slack thread 115 controlling mechanism for the looper thread including a cam fixed to said looper supporting shaft and moving therewith, thread guides with which said cam cooperates, a sleeve mounted on said shaft to move endwise therewith and carrying said thread 120 125 130

guides, and means for preventing said sleeve from oscillating with the shaft.

15. A sewing machine including in combination a cylindrical work supporting arm, a looper shaft extending endwise thereof, loopers mounted on said shaft, said looper shaft being oscillated to move the loopers into and out of their needle thread loops and being moved endwise to give said loopers a needle avoiding movement, a slack thread controlling mechanism for the looper thread including a cam fixed to said looper supporting shaft and moving therewith, thread guides with which said cam cooperates, a sleeve mounted on said shaft to move endwise therewith and carrying said thread guides, means for preventing said sleeve from oscillating with the shaft, a pull off mechanism for the looper threads including a pull off cam, thread guides cooperating with said pull off cam, said pull off cam being operated by said looper shaft, and a thread clamp between the pull off cam and the slack thread controlling mechanism, and means operated by the endwise movement of the looper shaft for clamping the thread.

16. A sewing machine including in combination a cylindrical work supporting arm, a looper shaft extending endwise thereof, loopers mounted on said shaft, said looper shaft being oscillated to move the loopers into and out of their needle thread loops and being moved endwise to give said loopers a needle avoiding movement, a slack thread controlling mechanism for the looper thread including a cam fixed to said looper supporting shaft and moving therewith, thread guides with which said cam cooperates, a sleeve mounted on said shaft to move endwise therewith and carrying said thread guides, means for preventing said sleeve from oscillating with the shaft, a pull off mechanism for the looper threads including a pull off cam, thread guides cooperating with said pull off cam, said pull off cam being operated by said looper shaft, a thread clamp between the pull off cam and the slack thread controlling mechanism, and means operated by the endwise movement of the looper supporting shaft for clamping the thread, said slack thread controlling mechanism, said pull off mechanism and said thread clamping mechanism all being located within said cylindrical work supporting arm.

17. A sewing machine including in combination, a cylindrical work supporting arm, a looper shaft extending longitudinally thereof, a thread carrying looper carried

thereby, said shaft being adapted to oscillate and move endwise for vibrating and moving said looper laterally, and a slack thread controlling mechanism including an oscillating member, and thread guides associated therewith located adjacent the end of the work supporting arm near the thread carrying looper, said slack thread controlling mechanism being movable with the shaft in its endwise movement which gives the lateral movements to the looper whereby the lateral movements of the looper will not affect the control of the thread by said thread controlling mechanism.

18. The combination with a cylindrical work supporting arm, a thread carrying looper located at the free end of said arm, means for oscillating said thread carrying looper and for moving said thread carrying looper laterally, slack thread controlling mechanism for the looper located adjacent the end of the work supporting arm, and means for moving said slack thread controlling mechanism bodily with the looper on its lateral movements.

19. A sewing machine including in combination, a cylindrical work supporting arm, a looper shaft extending longitudinally thereof, a thread carrying looper carried thereby, said shaft being adapted to oscillate and move endwise for oscillating the looper and moving the same laterally, a slack thread controlling mechanism for the looper thread located adjacent the looper and actuated by the looper shaft, a pull-off mechanism for the looper thread actuated by the looper shaft, and a thread clamp disposed between the pull-off mechanism and the slack thread controlling mechanism operated by said looper shaft.

20. A sewing machine including in combination, a cylindrical work supporting arm, a looper shaft extending longitudinally thereof, a thread carrying looper carried thereby, said shaft being adapted to oscillate and move endwise for oscillating the looper and moving the same laterally, a slack thread controlling mechanism operated by the oscillations of said looper supporting shaft, a pull-off mechanism actuated by the oscillations of said looper supporting shaft, and a thread clamp located between said pull-off mechanism and said slack thread controlling mechanism operated by the endwise movement of said looper supporting shaft.

In testimony whereof, I affix my signature.

JAMES R. MOFFATT.
